UNITED STATES PATENT OFFICE.

CHARLES A. MAHER, OF WALLOWA, OREGON.

SOAP AND APPLICATOR HOLDER.

1,348,025.

Specification of Letters Patent. Patented July 27, 1920.

Application filed April 10, 1919. Serial No. 289,166.

To all whom it may concern:

Be it known that I, CHARLES A. MAHER, a citizen of the United States, residing at Wallowa, in the county of Wallowa and 5 State of Oregon, have invented new and useful Combination Soap and Applicator Holders, of which the following is a specification.

This invention relates to tonsorial appliances, and more particularly to a device for holding a stick of shaving soap which may be readily removed for application to the face and having means contained within said device for rubbing the applied soap 15 into a lather.

The object is to provide such a holder or container which will keep a stick of soap in a sanitary condition, said holder having a removable cap formed to be readily 20 grasped by the hand and carrying a lathering device which, when the cap is secured in position upon the holder, is housed within the latter and is ready for instant use when removed therefrom.

25 A full and complete understanding of the invention may be obtained from a consideration of the following detailed description, taken in connection with the accompanying drawing forming a part of this specification; it being understood that while the drawing shows a practical form of the invention, the latter is not confined to strict conformity therewith, but may be changed or modified, so long as such changes or modifications mark no material departure from the salient features of the invention, as specifically pointed out in the appended claims.

30 In the drawing, in which similar reference characters designate corresponding parts throughout the several figures:—

Figure 1 is a perspective view of the combination shaving soap and applicator holder with the cap screwed in position thereon.

Fig. 2 is a vertical longitudinal sectional view of the same.

Fig. 3 is a detail perspective view of the cap removed and more clearly illustrating the applicator carried thereby.

The present invention is designed to overcome the annoyance caused by the necessity of having separate receptacles or containers for shaving soap and shaving brush, during the operation of shaving. This annoyance is especially apparent when traveling, as the 55 two containers necessarily occupy more space in traveling bag or trunk, one being

often carried along while the other is forgotten, and in crowded wash rooms on trains and cramped state rooms aboard ship, the care of and proper cleansing of a few parts 60 or containers has been found advantageous.

The combination holder of the present invention provides means for housing both the shaving soap and means for producing a lather upon the face after the soap is 65 applied and allows of the ready removal of either, or both, from the casing and prevents the loss of either after the parts are secured together.

As illustrated in the drawing, a metallic 70 tubular receptacle 1 is provided, having a bottom 2 integrally connected therewith as through the medium of a well-known spinning process, whereby the bottom and wall of the tubular member are formed of a 75 single sheet of thin metal, the point of junction providing an annular, interior groove for the reception of a paper disk 3 seated within said groove and thus prevented from jarring loose from such seat. An inner 80 tubular lining 4 of paper is placed within the tube 1, and such paper lining, together with the disk 3 are adapted to prevent corrosion of the inner walls of the receptacle by contact with the stick of soap, indicated 85 at 5, as well as to preserve the sanitary condition of said stick of soap. The features thus far described form no part of my invention, and I do not wish to be restricted thereto. 90

At the top, open end, the tube 1 is stamped or pressed into a thread 6 into which is adapted to be screwed the depending threaded portion 7 of a metallic cap 8, produced likewise of thin sheet metal and having intermediate its height, an annular milled rib 9, formed by pressing the metal outwardly in a well-known manner and adapted to facilitate the screwing or unscrewing action of the cap in applying or removing the 100 same.

The upper portion of the cap member, above the milled rib 9 is formed into an upstanding knob 10 of any desired contour or formation and adapted to form a handle to 105 be grasped by the hand of the operator, while in the act of lathering the face, in a manner to be explained.

A lathering device, formed of rubber having a solid or homogeneous base portion 11 and provided with peripheral threads is adapted to be screwed into the threads of 110

the cap member 8 and to be carried thereby, the said rubber base portion 11 being integrally connected to a depending lathering portion 12 which is composed of the same 5 rubber but formed into that variety known as sponge rubber, which is of a porous nature and has been found well adapted for the production and application of a soap lather upon the face for the operation of 10 shaving.

Upon removal of the cap from the container 1, the stick of soap may be easily removed and applied to the moistened face, when the lathering device is already at 15 hand, and the same may then be dipped into water and applied to the face in much the same manner as an ordinary brush when, by experience it has been found that the sponge-like nature of the rubber will produce the stiff, creamy, lasting lather so much 20 desired by persons when shaving.

The sponge rubber lathering device may be easily cleansed and kept in a sanitary condition at all times, and if necessary, may 25 be removed from the cap for the purpose of cleansing and has none of the disadvantages of the bristle brush in common use for shaving. It will be seen that a simple, cheap and convenient device has been provided for 30 the purpose stated whose advantages will be appreciated especially by the traveling public.

If it is desired to have a longer handle than that provided by the cap alone, the 35 operator may insert the tapered knob 10 into the open end of the tube 1 until the rib 9 bears against the end thereof, when the said cap together with the lathering device will be frictionally held therein.

40 What is claimed is:—

1. A combined shaving soap and applicator holder comprising a receptacle for the soap, open at one end and closed at the other, a cap member for closing the open

end of said receptacle, said cap member being provided with a threaded socket at one end, threads on the open end of the receptacle to be engaged by the threads on the socket of the cap member, and an applicator having its inner portion exteriorly threaded 50 to engage the threads of the socket, and having a projecting extension.

2. A combined shaving soap and applicator holder comprising a tubular receptacle closed at one end and open at the other and 55 adapted to hold soap, a cap member having a handle portion formed on its outer side, which handle portion is adapted to be fitted into and held by the open end of said receptacle, said cap member being provided with 60 a socket at its inner end also adapted to be held by the open end of said receptacle, and an applicator secured in said socket and adapted to be removed with the cap member from the receptacle and used as a brush. 65

3. A combined shaving soap and applicator holder comprising a tubular receptacle closed at one end and open at the other, and adapted to hold soap, a cap member having 70 a handle portion formed on its outer side and adapted to be fitted into the open end of said receptacle, said cap member being provided with a threaded socket at its inner end, and an applicator secured in said socket 75 and adapted to be removed with the cap member from the receptacle and used as a brush, said applicator having a solid or homogeneous base portion provided with threads for engagement with said socket, and an integrally connected projecting portion. 80

In testimony that I claim the foregoing as my own I have hereto affixed my signature in the presence of two witnesses.

CHARLES A. MAHER.
